UNITED STATES PATENT OFFICE.

JOHN P. L'HOMEDIEU, OF SETAUKEET, NEW YORK.

CULTIVATOR.

SPECIFICATION forming part of Letters Patent No. 436,795, dated September 23, 1890.

Application filed July 5, 1889. Serial No. 316,518. (No model.)

To all whom it may concern:

Be it known that I, JOHN P. L'HOMEDIEU, of Setauket, in the county of Suffolk and State of New York, have invented a certain new 5 and useful Improvement in Cultivators, of which the following is a specification.

I will describe a cultivator embodying my improvement and then point out the novel features in claims.

10 In the accompanying drawings, Figure 1 is a side elevation of a cultivator embodying my improvement. Fig. 2 is a plan or top view of the same. Fig. 3 is a vertical transverse section of one part or section of the same, taken at the plane of the dotted line $x-x$, Fig. 2, and looking in the direction indicated by the arrow at the end of this line. Fig. 4 is a longitudinal section taken at the plane of the dotted line $y-y$, Fig. 2. Fig. 5 is a vertical 15 section of a bolt forming part of the cultivator. Fig. 6 is a side elevation of a cultivator of another kind. Fig. 7 is a plan or top view of the cultivator shown in Fig. 6.

Similar letters of reference designate corresponding parts in all the figures.

20 I will first describe the cultivator represented by Figs. 1, 2, 3, 4, and 5. It consists, essentially, of two parts. One part A comprises a number of drag-bars a . The other 25 part B is a wheeled carriage, which is connected to the part A first mentioned.

The part A, as before stated, comprises a number of drag-bars. These are inclined downwardly at an obtuse angle from the front 30 to the rear, the rear faces being shown as abrupt. The under sides or edges of these bars are preferably rounded at the extremities where they join the ends of the bars, as may be seen by reference to Fig. 3. The angle at 35 the junction of the faces of each of these drag-bars preferably has secured to it a shoe a' , of steel or other suitable metal, to increase its durability.

The cross-bars a are shown as connected together by longitudinal bars a^2 . I have shown two of these bars. The under side of these bars a^2 may advantageously be recessed to receive the upper sides of the drag-bars. The drag-bars and the longitudinal bars a^2 may 40 be secured together by bolts or other devices.

C designates a shackle, which may be made

of any suitable metal bent between the ends to form an eye, and having its two end portions bent to diverge and turned at the extremities so as to form pivotal connections 55 with eyebolts c , here shown as secured in the forward portions of the longitudinal bars a^2 of the drag A. This shackle, owing to its pivotal connection with the drag, may swing upwardly and downwardly. The eye of the 60 shackle C has pivotally connected to it a clevis D. To the bolt of this clevis the whiffle-tree or harness of an animal or animals employed to draw the cultivator through the field may be attached.

65 The wheeled carriage or section B is shown as consisting of a pair of wheels b , fitted to an axle b' . To the axle b' a block b^2 is secured. It is here shown as arranged upon the upper side of the axle. It may advantageously be made of wood. Connected with it are two bars b^3 , which may also be made of wood and extend at right angles to the axle, and hence forwardly and backwardly. These bars b^3 are connected by a bar b^4 , extending 70 parallel to the axle, and also by a bar b^5 , which likewise extends parallel with the axle. A pole b^6 extends under the bars b^5 and b^4 and under the axle. It is shown as held to the axle by means of a loop or strap b^8 , which 75 may be made of any suitable metal and secured to the axle. It is shown as similarly secured by a loop or strap b^7 to the bar b^4 . The pole b^6 , owing to its being connected in the manner described with the axle and with the bar b^4 , 80 may be slid in the direction of its length so as to project a greater or less distance in front of the bar b^4 . A bolt b^9 , passed through the bar b^4 , may be engaged with any one of a number of holes with which the pole is provided 85 so as to secure the pole in the different positions into which it may be adjusted relatively to the bar b^4 . A seat b^{10} is supported by the bars b^8 . As here shown, it does not rest directly upon the bars, but upon rails or guides 90 b^{11} , which are affixed to the bars and extend lengthwise thereof. The seat is shown as having eyes b^{12} , which engage with the rails b^{11} . The seat, therefore, can be adjusted over the axle or more or less in front of the axle. 95 It may be secured in position by any suitable clamp, or it may be adjusted and maintained

- in position by the occupant. The pole b^6 is provided with a pin b^{13} and an eye b^{14} . The pin b^{13} engages with a plate or flange b^{15} , which is formed with a two-armed bolt b^{16} .
- 5 This two-armed bolt enters sockets provided in a bar a^3 , which is secured to and extends between the two bars a^2 and about midway of their length, so that the weight desired will be approximately near the center and cause 10 the drag to bear evenly on the ground. The double-armed bolt will be incapable of turning, but the pin b^{13} can turn relatively to it; hence the wheeled carriage or section B can swing relatively to the drag-section A.
- 15 A chain E is secured at one end to the eye b^{14} of the wheeled carriage or section B, and passes thence through the clevis D, and at the end is fastened to itself. This chain secures the wheeled carriage or section B to the 20 clevis D so that the draft of the animal or animals shall be not only upon the drag-section A but upon the section B. The drag pulverizes the earth and also grades and levels it. The animal or animals may be guided from 25 the wheeled carriage-section B.
- The wheels of the carriage-section B are considerably back of the drag-section. They are intended to be large and light so as not to seriously affect the soil. By adjusting the 30 connection of the bar b^4 with the pole the distance from the wheels of the drag-section may be varied. The draft will be divided between the drag-section and the wheeled carriage-section so that the animal or animals cannot 35 lift the drag. It will be seen that there will be no weight upon the animal or animals. The seat may be adjusted to produce exactly the weight which it is desired to exert upon the drag-section. Of course the wheeled section 40 can adjust itself to the drag-section for passing around curves.
- In Figs. 6 and 7 I have shown the same construction of wheeled carriage-section B, but instead of the form of drag-section A which 45 was represented in the primary example of my improvement I have shown a drag-section in the form of a harrow. The two sections are combined in this example of my improvement as in the other. The shackle C is of 50 substantially the same construction as that

in the first example of my improvement, although here, instead of having its ends bent to form pivots engaging with the eyebolts c, the ends embrace a bolt which extends through the eyebolts c.

55

I have shown the harrow as provided with eyebolts G from the rear bar. With either of these eyebolts may be engaged a lever H, having a pointed end and made of such length as to enable it to bear upon the bar b^5 of the 60 carriage-section B for a fulcrum and to extend within reach of the driver. By engaging the lever with one of the eyebolts and oscillating it upon the bar b^5 as a fulcrum, either side of the harrow may be tilted at will during its operation, or, if preferable, while it is at rest.

65

All the advantages of regulating the weight upon the drag-section in the first example of my invention can be realized with the harrow 70 in the second example of my invention.

70

What I claim as my invention, and desire to secure by Letters Patent, is—

1. In a cultivator, the combination, with a carriage-section, of a drag-section having a 75 shackle pivoted thereto, a clevis, a chain, and a double-armed bolt uniting the drag and carriage sections, substantially as specified.

2. In a cultivator, the combination of a drag-section having rearwardly-inclined bars, 80 a carriage-section connected to and bearing upon the drag-section near its center, and a draft attachment engaging with the carriage-section and with the drag-section, whereby the strain is divided equally upon the drag- 85 section and carriage-section, substantially as specified.

3. In a cultivator, the combination of a drag-section, a carriage-section, and a double-armed bolt b^{16} , engaging with the drag-section, 90 and a pin on the carriage-section engaging with a flange or plate of the double-armed bolt, the said carriage-section bearing downwardly on the drag-section, substantially as specified.

JOHN P. L'HOMEDIEU.
